UNITED STATES PATENT OFFICE

CHARLES MORTON, OF PAWTUCKET, RHODE ISLAND

SPINNING FRAME

Application filed February 6, 1930. Serial No. 426,299.

This invention relates to improvements in means for driving the draft rolls in yarn drafting machines or frames, such for instance as spinning frames, roving frames, intermediate frames, slubbing frames, and the like, and which is an improvement on my prior Patents Nos. 1,619,985 and 1,619,986, both dated March 8, 1927; and the object of my present invention is to provide simple and effective means whereby a group of draft rolls may be formed of very small diameters to be set close together so as to reduce the distance between their nipping centers to the minimum, to better support the roving being drafted, and to employ another draft roll thru which the intermediate roll of this group may be positively driven, by which construction an increased draft on the roving may be obtained over those set more widely apart and a relatively coarse roving used and drawn down to a relatively fine yarn and at the same time produce a yarn product of uniform size and quality.

With these and other objects and advantageous features in view, the invention consists of a novel arrangement of parts more fully disclosed in the detailed description following, in conjunction with the accompanying drawings, and more particularly set forth in the appended claims.

In the accompanying drawings:

Fig. 1 is a side elevation showing a group of draft rolls in section and an arrangement of gear drive thru a break draft roll to the intermediate rolls of said draft roll group.

Fig. 2 is a top view illustrating the general arrangement of the group of draft rolls and a separate break draft roll thru which the intermediate roll of the group is driven from the gearing at the head end of the machine.

Fig. 3 is a diagrammatic view illustrating the general arrangement of the driving gears and the group of draft rolls also the break draft roll thru which the intermediate gear of the draft roll group is positively driven.

Fig. 4 shows the lower intermediate roll which is provided with a tongue and grooved at its opposite ends thru which it is connected to the ends of the corresponding aligned rolls.

Fig. 5 is an enlarged view illustrating the

tongue and groove connecting arrangement of the rolls, which connecting construction is mounted in a supporting bearing or journal.

Fig. 6 is a section on the line 6—6 of Fig. 5, showing the tongue and groove construction in its bearing and an oil hole communicating therewith.

It is found in the operation of the usual frames for draft rolls such for instance, as spinning frames, roving frames and other frames of this general character, necessary to set the draft rolls relatively wide apart in order to be able to mount the driving gears on the ends thereof of sufficient size and strength to operate the rolls in a practical way, but by this old construction the distance between the centers or nips of the back and front draft rolls must necessarily be so great as to insufficiently support the sliver between them thus materially limiting the amount of draft on the roving thereby necessitating the use of relatively fine hanks or roving to prevent a break down during a drawing operation and also prevent the forming of thick and thin places in the yarn.

The above difficulties have been overcome in a practical way by the use of two sets of draft rolls with a set of intermediate rolls between them forming a cooperating group of drafting rolls all of a relatively small diameter so that they may run very close together to reduce the distance between their nips or centers to the very minimum and to permit the intermediate rolls of this group to be driven thru a cooperating break draft roll.

By this construction, the intermediate rolls serve as a practical support for the roving between its draft rolls during the drawing operation and so prevents the roving from breaking down thus permitting a finer yarn of uniform size and quality to be obtained from a relatively coarse roving and eliminating the preparation of the finer hank roving thus materially reducing the cost of preparing the stock.

In order to overcome the difficulty of driving closely set rolls from the head end of the machine, I have mounted this set of so-called break draft rolls to the rear of the group

of draft rolls, the lower roll of this set of break draft rolls being geared to drive the intermediate rolls of the group; and the following is a detailed description of the present embodiment of my invention and showing one arrangement of rolls and driving mechanism therefor, whereby these advantageous results may be obtained.

With reference to the drawings, 10 and 11 10 designate respectively the bottom and top front rolls, and 12 and 13 the bottom and top back rolls of the draft roll group. Intermediate these two sets of rolls the upper and lower intermediate rolls 14 and 15 are set, 15 both of which are preferably of relatively small size and are preferably covered with leather, cork, or other soft material, these small intermediate rolls permitting the back and front rolls of the group to be set much 20 closer together than has heretofore been possible in machines of this character.

A new feature of my present invention is my improved method or means of driving these intermediate rolls, which is that of providing a lower so-called break draft roll 16 25 located to the rear of the rear draft rolls 12 and 13 of the group. One end of this break draft roll being connected at the head end of the frame from the driving mechanism of 30 the rest of the machine thru the large gear 19, on the end 20 of the front rolls 10, thence thru the pinion 21, large gear 22, pinion 23 and large gear 24 which is mounted on the end 25 of this break draft roll 16. The opposite end of this break draft roll is connected thru gear 26, idler 27 and gear 28, to 35 positively drive the lower intermediate roll 14 at a speed a little greater than that of the back roll 12 of this group, which back roll 12 is driven from the break roll shaft 25 from the gear 29 thru pinion 30 to the gear 31 on the back draft roll 12 of this group.

The gears at the head end of this machine may be arranged as change gears to vary the 45 relative speeds of the different draft rolls to obtain the drafting ratio desired.

Cooperating with this lower break draft roll 16 is herein shown a relatively heavy top roll 32 mounted in the bearing 33 and which 50 cooperates with the bottom roll 16 to assist in starting or breaking the draft of the roving as it passes therebetween to the group of draft rolls ahead of it. The tension may be applied to the top rolls 11 and 13 in the usual manner, the construction herein shown being that tension is applied to the saddle 34 thru the connection 35, lever 36 and weight 37. All of 55 these rolls are mounted in suitable bearings in the stands 38 and the different groups of rolls 60 along the machine may be connected together by any suitable means, the ends of the intermediate rolls 14 being herein shown as being provided with a tongue member 39 at one end and at its opposite end with a groove 40, 65 which when arranged to interlock with each

other may both be journaled in the single bearing 41 thereby providing a simple means of connecting up these rolls end to end and at the same time providing a single bearing which may support the opposite interlocking ends of both rolls.

My improved construction of yarn draft frame or machine is extremely simple and provides a most practical mechanism by which the intermediate roll of the group of draft rolls may be positively driven thru a draft roll other than those of the group and from the head end of the machine thru properly arranged gearing and at the same time permit of the use of gears of a suitable size at the other end of the roll to readily transmit the power required.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a yarn drafting machine, a group of draft rolls, comprising a pair of front rolls, a pair of back rolls, and a pair of intermediate rolls all arranged in closely spaced relation to run with their peripheries just clear of each other, gears for driving said front and back rolls at different relative speeds, and a back feed draft roll thru which said pair of intermediate rolls is driven.

2. In a yarn drafting machine, a group of draft rolls, comprising a pair of front rolls, a pair of back rolls, and a pair of intermediate rolls all arranged in closely spaced relation to run with their peripheries just clear of each other, a back draft roll, drive shafts for said rolls, gears for driving said front and back rolls at different relative speeds, the back feed draft roll being driven from one end of the machine from the front roll drive shaft and the intermediate roll of said group being driven from the opposite end of the machine thru back feed draft roll.

3. In a yarn drafting machine, a group of draft rolls, comprising a pair of front rolls, a pair of back rolls, and a pair of intermediate rolls all arranged in closely spaced relation to run with their peripheries just clear of each other, gears for driving said front and back rolls at different relative speeds, a back feed draft roll thru which said pair of intermediate rolls is driven, and a weight roll on the lower back feed draft roll located with its periphery just clear of that of the back roll of said group.

4. In a yarn drafting machine, a group of draft rolls, comprising a pair of front rolls, a pair of back rolls, and a pair of intermediate rolls all arranged in closely spaced relation to run with their peripheries just clear of each other, a pair of back feed draft rolls,

gears for driving said front and said back feed draft rolls, and means for driving the back and intermediate rolls thru the driven back feed draft roll from opposite ends of the machine.

5 5. In a yarn drafting machine, a group of draft rolls, comprising a pair of front rolls, a pair of back rolls, and a pair of intermediate rolls all arranged in closely spaced relation to run with their peripheries just clear of each other, a back feed draft roll, drive shafts for said rolls, means including gears for driving said back feed draft roll from the front roll drive shaft, gears at one end of the machine for driving said back rolls from said back feed draft roll drive shaft, and gears at the opposite end of the machine for driving said intermediate rolls for said back feed draft roll drive shaft.

10 15 20 In testimony whereof I affix my signature.
CHARLES MORTON.
